US0D1026476S

(12) **United States Design Patent** (10) **Patent No.:** **US D1,026,476 S**
(45) **Date of Patent:** ** *May 14, 2024

(54) **SHEET MATERIAL**

(71) Applicant: **SONY INTERACTIVE ENTERTAINMENT INC.**, Tokyo (JP)

(72) Inventor: **Satoshi Aoyagi**, Tokyo (JP)

(73) Assignee: **SONY INTERACTIVE ENTERTAINMENT INC.**, Tokyo (JP)

(*) Notice: This patent is subject to a terminal disclaimer.

(**) Term: **15 Years**

(21) Appl. No.: **29/751,566**

(22) Filed: **Sep. 22, 2020**

(30) **Foreign Application Priority Data**

Apr. 3, 2020 (JP) ..... 2020-007074 D

(51) **LOC (14) Cl.** **05-06**
